[57] CLAIM

The ornamental design for a mop bucket accessory handle, as shown and described.

DESCRIPTION

FIG. 1 is a perspective drawing showing our new design for a mop bucket accessory handle and wherein the matter shown in phantom line comprises no part of the invention; FIG. 2 is a front elevation drawing thereof, the rear elevation drawing being a mirror image;

FIG. 3 is a right side elevation drawing thereof;

FIG. 4 is a left side elevation drawing thereof;

FIG. 5 is a bottom view thereof; and,

FIG. 6 is a top view thereof.
